UNITED STATES PATENT OFFICE.

JOHN D. LAWRENCE AND STANLEY W. NICHOLSON, OF TOLEDO, OHIO, ASSIGNEES TO THE DURA COMPANY, OF TOLEDO, OHIO, A CORPORATION OF DELAWARE.

WINDOW-CONTROL MECHANISM.

1,419,937.

Specification of Letters Patent. Patented June 20, 1922.

Application filed October 11, 1920. Serial No. 416,245.

To all whom it may concern:

Be it known that we, JOHN D. LAWRENCE and STANLEY W. NICHOLSON, citizens of the United States of America, residing at Toledo, in the county of Lucas and State of Ohio, have invented certain new and useful Improvements in Window-Control Mechanism, of which the following is a specification, reference being had therein to the accompanying drawings.

This invention relates to window control mechanism, and more particularly to mechanism for vertically adjusting windows of motor vehicles.

15 It is the object of the invention to provide a comparatively simple mechanism adapted to be enclosed within the lower portion of a vehicle door to actuate the vertical travel of a window member in the upper portion of 20 the door and serving to automatically maintain such window member in any desired position of adjustment.

25 A preferred embodiment of the invention is illustrated in the accompanying drawing wherein;

Figure 1 is an interior view of a motor vehicle door of the sliding window type equipped with the herein described control mechanism and having a portion of the 30 trimming broken away to disclose the location of said mechanism within the chambered lower portion of said door;

Figure 2 is an enlarged view of the control mechanism shown in Figure 1;

35 Figure 3 is an sectional view taken upon line 3—3 of Figure 1.

Figure 4 is a sectional view taken upon line 4—4 of Figure 2.

40 In these views the reference character A designates a motor vehicle door, the frame of which has uprights A' and A² at its respective vertical edges; B is a window opening in the upper portion of said door for which a closure is formed by a vertically 45 slideable plate of glass C which in its lowered position enters a chamber D formed in the lower portion of said door. To counter-balance the window member C so that it may be adjusted with less effort there is 50 positioned within the chamber D the counter-balancing arm E pivoted at one end upon the upright A' and bearing upwardly upon the lower edge of the glass C at its other extremity. A coiled spring F exerts 55 an upward pull upon said arm such as to

substantially counter-balance the weight of the glass. The actuating mechanism for the glass comprises an arm G pivoted at one end upon the upright A² and engaging at its other end a channeled sheet metal strip G', secured to the bottom edge of the glass. A nut H is swiveled upon the arm G adjacent its pivoted end and engaged by the threaded portion I' of the upwardly extending stem I, the upper portion of which is journaled 60 in a cylindrical mounting J which is swiveled in a cross piece K of the door frame. The swivel mounting J comprises the complementary members J' and J² secured to each other by screws L and respectively provided with annular flanges J³ between which is engaged a portion of the frame member K marginal to the aperture of said member in which the mounting J is swiveled. The stem I is adapted to be rotated through a 65 pair of pinions L', the shaft M of the driving pinion being journaled in the mounting J, transversely to the stem I and carrying the actuating handle M'.

All the described mechanism is to be concealed within the chambered lower portion 80 of the door excepting the handle M' which is adjacent to the interior face of the door.

In the operation of the described control mechanism, when it is desired to adjust the 85 window member C the handle M' is rotated. This rotation is transmitted through the pinions L' to the stem I, which through engagement with the nut H effects the raising or lowering of the arm G, according to the 90 direction of the rotation of the handle M'. As the nut H is constrained to travel in a circular arc, the stem I swings through a slight angle of the vertical, the divergence 95 from the vertical being a maximum when the arm G is horizontal as indicated in dash lines in Figure 2. The necessity for swivel mounting of the nut H on the arm G and for the swiveling of the member J arises from this slight angular movement of the 100 stem I. It will be apparent that the engagement of the stem I with the nut H provides an automatic lock such as will serve to maintain any position to which the window member C may be adjusted.

105 The feature of forming the actuating mechanism and counter-balancing mechanism as separate units, each unit being independently mounted in opposed relation upon the uprights A' and A² results in a 110

desirable compactness and facilitates installation.

What we claim as our invention is:

1. In a window control mechanism, the combination with a pivotal window lifter arm, of a nut swiveled on said arm, a stem extending from said arm, having a threaded portion engaging said nut, a swivel mounting providing a journal bearing for said stem, adapting the stem to swing in the plane of said arm, a crank mounted upon said bearing, and gearing carried by said bearing for actuating said stem from said crank.
2. In a window control mechanism, the combination with a pivotal lifter arm, of a stem extending from said arm having a threaded portion engaged with the arm, a swivel mounting for said stem, adapting the stem to swing in the plane of said arm, a crank journaled in said mounting, transversely to the stem and gearing carried by said mounting for actuating said stem from said crank.
3. The combination of a slidable window member, a frame having a chamber receiving said window member in the open position of the latter, and a controlling mechanism for operating said window comprising a handle mounted upon the frame near the upper part of the chamber, a threaded stem, a drive connection between said handle and said threaded stem for rotating the latter upon rotation of the former, said stem projecting downwardly within said chamber, a fixed member within said chamber and arranged at one side of said stem, a single control arm having one end fulcrumed on said fixed member and extending across said threaded stem and having its opposite end portion in operative engagement with said window, and a threaded connection between said threaded stem and said control arm, said controlling mechanism including two floating connections for permitting said control arm to be raised and lowered through movements of the handle without binding said threaded stem, one of said floating connections being located between the threaded stem and the controlling arm.
4. The combination with a slidable window member, of a frame having a chamber receiving said member in its open position, a control arm for said member arranged within said chamber and adapted to swing in a plane substantially parallel to that of the window member, a fulcrum support for said arm directly engaged by the arm and stationary within said chamber, a rotative threaded stem, a nut engaging said stem carried by the arm, and adapted to rock relative thereto, and means preventing binding of the stem due to the relative angular movement of the arm.
5. The combination with a slidable window member, a frame receiving said member in its open position, a control arm for said member fulcrumed at one end within said chamber to swing in a plane substantially parallel to the window member and having its fulcrum end restrained from movement in said plane transverse to the travel of the window member, a rotative threaded stem, a nut engaging said stem and attached to said arm and adapted to rock relative to the arm, and means for preventing binding of the stem due to the relative angular movement of the arm.
6. The combination with a slidable window member, a frame receiving said member in its open position, a control arm for said member fulcrumed at one end within said chamber to swing in a plane substantially parallel to the window member and having its fulcrum end restrained from movement in the direction of travel of the window member, a rotative threaded stem, a nut engaging said stem and attached to said arm and adapted to rock relative to the arm, and means for preventing binding of the stem due to the relative angular movement of the arm.
7. The combination with a slidable window member, of a frame having a chamber receiving said member in its open position, a control arm for said member arranged within said chamber and adapted to swing in a plane substantially parallel to that of the window member, a fulcrum support within said chamber for said arm, directly engaged by the arm and restrained from vertical movement, a rotative threaded stem, a nut engaging said stem carried by the arm, and adapted to rock relative thereto, and means preventing binding of the stem due to the relative angular movement of the arm.
8. The combination with a slidable window member, of a frame having a chamber receiving said member in its open position, a control arm for said member arranged within said chamber and adapted to swing in a plane substantially parallel to that of the window member, a bracket stationary within said chamber and providing a fixed fulcrum point for the arm, a rotative threaded stem, a nut engaging said stem carried by the arm, and adapted to rock relative thereto, and means preventing binding of the stem due to the relative angular movement of the arm.
9. The combination with a slidable window member, of a frame having a chamber receiving said members in its open position, an actuating mechanism for said window member within said chamber comprising a fixed fulcrum support and two parts, one having the nature of a control arm engaging said support and adapted to swing thereupon in a plane substantially parallel

to the window member, and the other being a threaded stem rotatably adapted to actuate said arm, provision being made for a movement of one of said parts in addition to the 5 described movements to permit the necessary travel of the point of application of power from the screw to the arm relative to said fulcrum support.

10. The combination with a slidable window member, of a frame having a chamber receiving said member in its open position, a control arm for said member arranged within said chamber and adapted to swing in a plane substantially parallel to that of 15 the window member, a rotative threaded stem, a nut attached to said arm and engaging said stem, and actuating means for said stem, provision being made for swinging of said stem in substantially the plane 20 of the arm to prevent binding of the stem.

11. The combination of a slidable window, a frame having a chamber receiving said window in the open position of the latter, a control mechanism for operating said

window comprising a rotating handle, a 25 threaded stem projecting within said chamber, a connection between said stem and said handle for effecting a rotation of the former upon the rotation of the latter, a single arm member arranged within said chamber, 30 a nut carried by the arm member and movable in relation thereto, said nut engaging said stem member, a mounting fixed in relation to the frame and to which the arm member is directly connected, whereby upon 35 raising and lowering of said arm member the latter will be caused to rock in a plane substantially parallel to the window member, and a mounting for the stem member fixed in relation to the chamber, the connection between one of said members and its mounting permitting movement of such member in relation to its mounting to prevent binding of said control mechanism.

In testimony whereof we affix our signatures. 45

JOHN D. LAWRENCE.

STANLEY W. NICHOLSON.
